[57] CLAIM

The ornamental design for a wireless telephone, as shown and described.

DESCRIPTION

FIG. 1 is a perspective view of a first embodiment of a wireless telephone showing my new design;

FIG. 2 is a top plan view thereof;

FIG. 3 is a left side elevational view thereof;

FIG. 4 is a front elevational view thereof;

FIG. 5 is a bottom plan view thereof;

FIG. 6 is a right side elevational view thereof; and

FIG. 7 is a rear elevational view thereof.

FIG. 8 is another perspective view thereof, wherein the microphone portion is in the extended position.

FIG. 9 is a perspective view of a second embodiment of a wireless telephone showing my new design;

FIG. 10 is a top plan view thereof;

FIG. 11 is a left side elevational view thereof;

FIG. 12 is a front elevational view thereof;

FIG. 13 is a bottom plan view thereof;

FIG. 14 is a right side elevational view thereof; and,

FIG. 15 is a rear elevational view thereof; and,

FIG. 16 is another perspective view thereof, wherein the microphone portion is in the extended position.

The portions of the article not shown in the drawing nor described in the specification form no part of the claimed design.
